UNITED STATES PATENT OFFICE.

ALONZO E. RHOADES, OF HOPEDEALE, MASSACHUSETTS, ASSIGNOR TO DRAPER CORPORATION, OF HOPEDEALE, MASSACHUSETTS, A CORPORATION OF MAINE.

QUICK-ACTING WARP STOP MECHANISM FOR WARPERS.

Application filed February 11, 1926. Serial No. 87,643.

This invention relates to improvements in warp stop mechanism for warpers and the general object of the invention is to provide the mechanism for immediately stopping the warper upon the falling of a drop wire by reason of a broken warp.

The breakage of a warp coming from the creel to the warper may occur near the beam upon which it is to be wound, or the warp may break in front of the stop motion and the trailing end carried on to the beam. In usual constructions where the stoppage of the warper is delayed after detection of a broken warp many yards of the warp are apt to be carried along before the warper is completely stopped so that in piecing the ends it is almost impossible not to cross them for if the ends are wound around the beam, or the broken end has to be found after it has been wound upon the beam, it is almost impossible to piece up and keep the warps in line. Consequently, frequently the warps are crossed. By the present invention the warper is stopped in a small fraction of the time required for the stoppage of the ordinary warper; consequently, there is much less run-over of the yarn. Furthermore, the prompt stoppage of the warper enables the broken end readily to be found before it has been wound upon the beam, thus saving a crossing of the warps.

The present invention comprises several different means for more quickly stopping the warper after detection of a broken warp, which means may be employed independently of each other, but preferably are used conjointly. First, detector mechanism is employed in which the falling drop wire engages and immediately arrests the moving detector bar in either direction of the movement thereof, instead of arresting the bar in only a single direction of its movement. Second, a yielding controller is employed, for transmitting movement from a continually moving vibrator to the movable detector bar, which is so connected to a knock-off device that the knock-off device will be actuated during either direction of movement of the vibrator to cause a stoppage of the warper. Third, a continually moving actuator is provided for the knock-off device having means operable at a greater speed than the speed of movement of the vibrator to actuate the knock-off device when engaged thereby and will, therefore, immediately

cause a stoppage of the warper. When, therefore, these instrumentalities are used conjointly a very prompt stoppage of the warper is effected.

In the preferred embodiment of the invention disclosed herein a novel form of drop wire mechanism is shown which is made the subject matter of a separate application for patent filed concurrently herewith Serial Number 87,642 and patented October 5, 1926, No. 1,601,881.

Other objects and features of the invention will more fully appear from the following description and the accompanying drawings and will be particularly pointed out in the claims.

The preferred embodiment of the invention is disclosed herein as applied to a warper of the usual type, only a sufficient portion of the warper frame and mechanism being illustrated to show the manner in which the present invention is associated therewith.

In the drawings:

Fig. 1 is an end elevation of a warper frame showing the invention applied thereto;

Fig. 2 is a plan view of the end portion of the warper illustrated in Fig. 1;

Fig. 3 is a sectional view on line 3-3 Fig. 1, viewed from the top; and,

Fig. 4 is a perspective view of the preferred form of drop wire and co-operating detector bars illustrated in Fig. 1.

The portion of the warper shown in Fig. 1 comprises an end frame 1 having mounted upon it a stand 2 in which the forward upper guide roll 3 is mounted, a bracket 4 upon which the under guide bar 5 is mounted, and a bracket 6 which is secured to the front of the end frame and is provided with a slot 7 to receive the journal of the front guide roll 8. A usual transverse bar 9 extends from one end frame to the other and is provided with a comb 10 between the reeds of which the warps are led. The warp 11 runs from the creel beneath the guide roll 3, over the guide bar 5, thence through the eyes of the drop wires and over the front guide roll 8 to the usual warper beam (not shown).

The preferred form of detector mechanism comprises two series or banks of drop wires 12 and 13, each of the drop wires 12 having at its upper end an eye 14 with a threading slot leading thereto, and at its

lower end an enlarged cylindrical portion which is pivotally mounted upon a drop wire bar 15 which extends from one end frame of the warper to the other. The drop wires 13 likewise are provided at their upper ends with eyes 16 and at their lower ends with enlarged cylindrical portions 17 which are pivotally mounted upon a drop wire bar 18. The drop wire bars 15 and 18 desirably are provided with cylindrical ends and with opposite flat faces throughout the section upon which the drop wires are pivotally mounted and the cylindrical bases of the drop wires are provided with slots 19 of sufficient width to pass over the flattened section of the drop wire bar so that the drop wires can be individually assembled upon and removed from the drop wire bar by merely rotating the drop wire bar sufficiently to permit such assemblage or removal. Normally the drop wire bars are rotated to a position which will prevent the drop wires from being detached therefrom during the operation of the warper.

The drop wire bars may be secured in adjusted positions by means of an arm 20 which is fixedly secured to the end of the drop wire bars and provided with a set screw 21 adapted to abut against the outer face of the end frame.

The detector bars, which co-operate with the drop wires, 12, desirably comprise a stationary bar 22 and a juxtaposed relatively movable bar 23 and similar stationary and relatively movable detector bars 24 and 25 co-operate with the drop-wires 13. Each of these detector bars desirably is provided with teeth presenting vertical adjacent faces spaced apart a sufficient distance to receive a falling drop wire therebetween so that when the drop wires engage the complementary teeth of the stationary and relatively movable detector bars the movable detector bar will be arrested immediately in either direction of its movement, thereby more quickly initiating the action of the mechanism for stopping the warper than in previous constructions.

Any suitable means may be provided for causing relative movement of the detector bars and for effecting a stoppage of the warper upon arrest of such movement. In the preferred construction illustrated the relatively movable detector bars 23 and 25 have extensions 26 and 27 which are not toothed and which are connected at their ends respectively to bearing blocks 28 and 29 mounted upon studs 30 and 31 extending upwardly from the horizontal plate 32 of a transmitter which is actuated by a continually moving vibrator to impart a reciprocatory movement to the detector bars. The transmitter plate 32 is pivotally mounted at approximately its center upon a vertical shaft 33, the upper end of which is mounted

in a bracket 34 secured to the end frame and at its lower end is mounted in a bracket 35 which also is secured to the end frame. An arm or post 36, which preferably is integral with the plate 32, extends downwardly therefrom and is provided with a laterally extending boss 37 having an upwardly extending stud 38 upon which is pivotally mounted a horizontally extending arm 39 which is connected by a pivot 40 to one end of a link 41, the other end of which is connected by a stud 42 to a sickle-shaped lever 43 which is actuated by a continually moving vibrator.

The sickle-shaped lever has an integral, upwardly extending arm 44 which is pivotally mounted at its upper end upon a stud 45 extending laterally from an arm 46 of the bracket 34 which is mounted upon the end frame. The reciprocatory movement imparted by the vibrator to the lower end of the sickle-shaped lever 43 oscillates this lever about its pivot 45 in parallelism with the plane of the end frame. The reciprocatory motion of the sickle-shaped lever is transmitted through the links 41 and 39 to the arm or post 36 which depends from the plate 32 which is pivoted upon the vertical shaft 33, thus oscillating the plate 32 about the axis of the shaft 33 and imparting a longitudinal reciprocatory movement of the respective movable detector bars 23 and 25.

The assemblage thus described may be broadly considered a transmitter for translating the oscillatory movement of the vibrator, which is in a plane parallel to the plane of the end frame, into a reciprocatory movement for the detector bars which is at right angles to the plane of the end frame.

Suitable means are provided for causing the arrest of either of the movable detector bars 23 or 25 to actuate a knock-off device to stop the warper. In the particular construction illustrated, the knock-off device comprises a depending arm 47 which is pivotally mounted at its upper end upon a stud 48 projecting laterally from the end of an arm 49 which is pivotally mounted upon a stud 50 upon a bracket 51 which is secured to the end frame. The bracket 51 desirably is provided with a lug 52 to limit the upward movement of the arm 49, and the depending knock-off device, and is also provided with a lug 53 in a position to be engaged by the arm 49 to limit the downward movement of the knock-off device 47. The lower end of the knock-off device is provided with a laterally extending stud 54 which engages the eye in one end of a rod 55, the other end of which is connected to the usual knock-off lever 56 of the warper which, when actuated, knocks off the shipper lever 57 and causes the stoppage of the warper in the usual manner.

Any suitable means may be employed for

moving the knock-off device 47 upon arrest of a detector bar to effect the stoppage of the warper. In the present invention means are provided which will cause a much quicker action of the knock-off mechanism than in previous constructions. In the preferred embodiment of the invention illustrated herein the knock-off device 47 is provided with an offset lower end 58, the horizontal portion of the offset being provided with a curved face 59 which engages an arcuate surface 60 of a controller in the form of an arm or lever 61 which is pivotally mounted at its opposite end upon a stud 62 extending from a lateral arm 63 of a continually moving vibrator 64. The vibrator 64 is pivotally mounted at its lower end upon a stud or shaft 65 and is provided at a short distance from the lower end with a lateral extension 66 which is connected by a pin and slot connection 67 to the upper end of an arm 68 which is rigid with the usual rock shaft 69 of the warper which is continually vibrated.

A spring 70, seated in a suitable socket in the shoulder at the upper end of the vibrator from which the arm 63 extends, engages at its upper end a complementary socket 71 extending upwardly from the under face of the central portion of the controller 61 and holds the controller in engagement with the lower end of the sickle-shaped lever 43 of the transmitter. The spring 70, by thus holding the controller in a raised position, also holds the knock-off device in an elevated position out of the path of a continually moving actuator 72 during the normal operation of the warper.

The continually moving actuator may be of any suitable construction and is so constructed as to actuate the knock-off device 47 when engaged thereby more quickly than if the knock-off device were actuated by the movement of the vibrator itself. In the preferred construction the actuator is in the form of a star wheel 72 which is fixedly secured upon a shaft 73 which is continuously rotated at a speed which will cause a prompt actuation of the knock-off mechanism when the knock-off device is engaged thereby. The star wheel actuator 72 is so located that its teeth 74 clear the lower end of the knock-off device 47 during the normal operation of the warper when the knock-off device is held in elevated position by the controller 61 which is forced upwardly by the spring 70. The controller 61 is provided with a cam-shaped upper face preferably in the form of a re-entrant angle presenting substantially symmetrically inclined flat faces 75 and 76. The lower end of the sickle-shaped arm 43 is provided with a cylindrical, lateral extension 77 which normally rests frictionally in the re-entrant angle. This spring-pressed controller 61 therefore constitutes a connection between the vibrator

64 and the arm 43 which yields to give away when the arm 43 is held stationary under the control of the detector mechanism. When, therefore, a reciprocating detector bar is arrested by a falling drop wire 70 rotary movement of the transmitter 36 about the axis of the shaft 33 is prevented and consequently oscillation of the sickle-shaped lever 43 is prevented so that the lower end thereof is held stationary. As the vibrator 75 moves continuously, the controller 61 will be forced downwardly by the end 77 of the then stationary sickle lever in either direction of its reciprocation. Such downward movement of the controller will permit the 80 knock-off device 47 to fall by gravity so that its lower end, which desirably is provided with a flat face 78, will extend into the path of the teeth 74 of the continually rotating actuator. Upon engagement of the lower 85 end of the actuator with a tooth 74 of the rotating actuator the knock-off device will be swung laterally (to the left in Fig. 1) and will thereby act through the rod 55 to cause the usual knock-off lever 56 to knock 90 off the shipper 57 and thereby stop the warper.

By reason of the construction thus described it will be obvious that a very prompt stoppage of the warper will be effected upon detection of a broken or unduly sagging warp for the reason that the detector bar will be arrested in either direction of its movement and will immediately stop the movement of the sickle lever 43. Such 95 arrest of the movement of the sickle lever in turn will actuate the controller 61 in either direction of its movement to permit the knock-off device 47 to drop into the path of the teeth of the rotating actuator. As the 100 rapidly moving teeth of the rotating actuator are arranged to actuate the knock-off device 47 an almost immediate actuation of the usual lever 56, which knocks off the shipper lever, is effected.

It will be understood that the particular embodiment of the invention disclosed herein is of an illustrative character and is not restrictive and that various modifications may be made in construction, form and operation of the various mechanisms herein described within the meaning and scope of the following claims. For example, the continually moving actuator may be made in various forms, either rotary or reciprocating. Other means may be employed for actuating the knock-off device and other types of controller and of transmitting mechanism may be employed. Other types of detector mechanism may also be employed which are so constructed as to be arrested by the falling drop wire during the movement thereof in either direction.

It will also be obvious that inasmuch as the present invention embodies three distinct

means for speeding up the mechanism for stopping the warper such means may be employed singly or in combination with any other, and that they are preferably, but not necessarily, used conjointly in the manner disclosed herein.

Having thus described the invention, what is claimed as new, and desired to be secured by Letters Patent, is:

1. Quick-acting warp stop mechanism for warpers comprising detector mechanism, a continually moving vibrator, a knock-off device, a continually moving actuator having means moving at greater speed than the speed of movement of said vibrator to actuate said knock-off device when engaged therewith and means controlled by said detector mechanism normally preventing engagement of said knock-off device with said actuator, but operable by said detector mechanism, upon detection of a broken or sagging warp, to cause such engagement and thereby effect a quick stoppage of the warper.

2. Quick-acting warp stop mechanism for warpers comprising detector mechanism, a continually moving vibrator, a knock-off device, a continuously rotating actuator having a plurality of means any one of which is adapted to actuate said knock-off mechanism when engaged therewith and means, including a connection yielding to give way, controlled by said detector mechanism normally preventing engagement of said knock-off device with said rotating actuator, but operable by said detector mechanism, upon detection of a broken or sagging warp, to cause such engagement and thereby effect a stoppage of the warper.

3. Quick-acting warp stop mechanism for warpers comprising detector mechanism, a continually moving vibrator, a knock-off device, a continually moving actuator having means operable at greater speed than the speed of movement of said vibrator to actuate said knock-off when engaged thereby, a yieldable controller normally retaining said knock-off device out of engagement with said actuator and means operable by said detector mechanism, upon detection of a broken or sagging warp, to cause said knock-off device to engage said actuator and thereby effect a stoppage of the warper.

4. Quick-acting warp stop mechanism for warpers comprising detector mechanism, a continually moving vibrator, a knock-off device, a continually moving actuator having means operable at greater speed than the speed of movement of said vibrator to actuate said knock-off when engaged therewith, a yieldable controller carried by said vibrator normally retaining said knock-off device out of engagement with said actuator and means operable by said detector mechanism, upon detection of a broken or sagging warp, to cause said controller to effect en-

gagement of said knock-off device with said actuator during the continuation of the same movement of the vibrator in which detection occurred and thereby effect a prompt stoppage of the warper.

5. Quick-acting warp stop mechanism for warpers comprising detector mechanism, a continually moving vibrator, a knock-off device, a continually moving actuator having means operable at greater speed than the speed of movement of said vibrator to actuate said knock-off device when engaged thereby, a yieldable controller arm pivotally mounted upon said vibrator engaging said knock-off device and normally retaining it out of engagement with said actuator and provided with a face presenting a re-entrant angle and means connected to said detector mechanism engaging the re-entrant angle of said controller operable upon detection of a broken or sagging warp to ride upon the inclined walls of the re-entrant angle and thereby cause said controller to yield and permit said knock-off device to engage said actuator, thereby effecting a stoppage of the warper.

6. Quick-acting warp stop mechanism for warpers comprising a reciprocating detector bar, drop wires for the respective warps adapted when dropped to arrest the movement of said detector bar, a continually moving vibrator, a knock-off device, a continually moving actuator having means operable at a greater speed than the speed of movement of said vibrator to actuate said knock-off device when engaged thereby, means for reciprocating said detector bar from said vibrator including a yieldable controller pivotally connected to said vibrator having means normally holding said knock-off device out of engagement with said actuator and having a face presenting a re-entrant angle and a transmitter connected to said reciprocable detector bar having means frictionally engaging said re-entrant angle and operable upon arrest of said detector bar to ride upon an inclined face of said controller and thereby depress said controller and cause engagement of the knock-off device with said actuator, thereby effecting a stoppage of the warper.

7. Quick-acting warp stop mechanism for warpers comprising drop wires for the respective warps, co-operating, parallel and juxtaposed stationary and longitudinally reciprocable detector bars provided with complementary teeth presenting vertical edges whereby a falling drop wire engaging the teeth of said bars will arrest the movable bar in either direction of its movement, a continually moving vibrator, a knock-off device, a continually moving actuator having means operable at greater speed than the speed of movement of said vibrator to actuate said knock-off when engaged thereby and means

controlled by said reciprocable detector bar normally preventing engagement of said knock-off device with said actuator, but operable upon arrest of said detector bar to 5 cause engagement therewith and thereby effect a stoppage of the warper.

8. Quick-acting warp stop mechanism for warpers comprising drop wires for the respective warps, co-operating, parallel and juxtaposed stationary and longitudinally reciprocable detector bars provided with complementary teeth presenting vertical edges whereby a falling drop wire engaging the teeth of said bars will arrest the movable bar 10 in either direction of its movement, a continually moving vibrator, a knock-off device, a continually moving actuator having means operable at greater speed than the speed of movement of said vibrator to actuate said 15 knock-off when engaged thereby, a yieldable controller moving with said vibrator, means operable by said detector bar when arrested in either direction of its movement to cause 20 said controller, during the continuation of

the movement of the vibrator in the same direction after the arrest of the movable detector bar occurs, to effect engagement of the knock-off device with said actuator and thereby promptly cause a stoppage of the warper.

9. Quick-acting warp stop mechanism for warpers, comprising detector mechanism, a continually moving vibrator, a knock-off device, a continually moving actuator operable to actuate said knock-off device when engaged therewith, a controller carried by said vibrator acting normally to prevent said knock-off from engaging said actuator, but operable by said detector mechanism, upon detection of a broken or sagging warp, to 40 cause such engagement during the continuation of the movement of the vibrator in the same direction in which said detection occurred, and thereby to effect a stoppage of the warper.

In testimony whereof, I have signed my name to this specification.

ALONZO E. RHOADES.
